(57) **ABSTRACT**

A new and distinct nectarine tree variety, *Prunus persica* var. *nucipersica*, cv. 'Sunecttwentyseven' is characterized by very early ripening, very large sized and sweet fruit having a medium brix value.

1 Drawing Sheet

1

Latin name of the genus and species claimed: *Prunus*
persica var. *nucipersica*.

Variety denomination: 'SUNECTTWENTYSEVEN'.

**BACKGROUND AND SUMMARY OF THE
INVENTION**

This invention relates to the discovery and asexual propagation of a new and distinct variety of nectarine, *Prunus persica* var. *nucipersica* cv. 'Sunecttwentyseven', as herein described and illustrated. The new variety was first selected as breeder number 'NE1816' by Terry A. Bacon and Terrence J. Frett near Wasco, Calif. in Kern County in June 2016. The variety was originated by controlled hybridization.

The new variety 'Sunecttwentyseven' is characterized by very early ripening, and very large sized and sweet fruit having a medium brix value.

The pollen parent is 'NE999Z' (unpatented breeding selection), and the seed parent is 'Sunecttwentytwo' (U.S. Plant Pat. No. 22,448). The parent varieties were first crossed in February 2012, the date of first sowing being February 2013 and the date of first flowering being February 2015. The new nectarine variety 'Sunecttwentyseven' was first asexually propagated by Terry A. Bacon and Terrence J. Frett near Wasco, Kern County, Calif. in February 2017 by dormant grafting.

The new variety 'Sunecttwentyseven' is distinguished from its seed parent, 'Sunecttwentytwo' in that the ripening of the fruit of the new variety starts 5 days earlier than the fruit of the seed parent. The new variety 'Sunecttwentyseven' also has a larger fruit weight of 175 g compared to a fruit weight of 145 g for 'Sunecttwentytwo'.

The new variety 'Sunecttwentyseven' is distinguished from its pollen parent, 'NE999Z' in that the fruit of the new variety ripens about 15 days earlier than that of the pollen

2

parent. The new variety 'Sunecttwentyseven' also has a larger fruit weight of 175 g compared to 155 g for 'NE999Z'.

The new variety 'Sunecttwentyseven' resembles 'Honey 5 May' (U.S. Plant Pat. No. 19,363) in that the fruit of both varieties has yellow flesh and ripens at about the same time. The new variety 'Sunecttwentyseven' differs from 'Honey May' in that the fruit of the new variety has a brix of 14% and a Brix:Acid ratio of 19, compared to a brix of 10% and a Brix:Acid ratio of 9 for 'Honey May'. The new variety 'Sunecttwentyseven' also differs from 'Honey May' in that the fruit weight of the new variety is 175 g compared to 133 g for 'Honey May'. The new variety 'Sunecttwentyseven' resembles 'Sunecttwentyone' (U.S. Plant Pat. No. 18,114) in that the fruit of both varieties has yellow flesh. The new variety 'Sunecttwentyseven' differs from 'Sunecttwentyone' in that the fruit of the new variety ripening starts about 13 days earlier than that of 'Sunecttwentyone' and has a brix of 14% and a Brix:Acid ratio of 19, compared to a brix of 12% and a Brix:Acid ratio of 14 for the fruit of 'Sunecttwentyone'.

The new variety 'Sunecttwentyseven' has been shown to maintain its distinguishing characteristics through successive asexual propagations by, for example, cuttings and grafting.

BRIEF DESCRIPTION OF THE PHOTOGRAPH

The accompanying color photographic illustration shows typical specimens of the foliage and fruit of the new nectarine variety 'Sunecttwentyseven'. The illustration shows the upper and lower surface of the leaves, an exterior and sectional view of a fruit divided across its suture plane to show flesh color, pit cavity and the stone. The photographic illustration was taken shortly after the fruit was picked and the colors are as nearly true as is reasonably possible in a color representation of this type.

DETAILED DESCRIPTION OF THE
PREFERRED EMBODIMENT

Throughout this specification, color names beginning with a small letter signify that the name of that color, as used in common speech is aptly descriptive. Color names beginning with a capital letter designate values based upon The R.H.S. Colour Chart published by The Royal Horticultural Society, London, England, 1986.

The descriptive matter which follows pertains to 3 year old 'Sunectwentyseven' plants grown in Wasco, Kern County, Calif., and is believed to apply to plants of the variety grown under similar conditions of soil and climate elsewhere. Observations were made in 2019.

TREE

General: (Measurements were taken on 3 year old trees unless otherwise noted.).

Size.—Large. Normal for most nectarine varieties.

Spread.—Normal for most nectarine varieties. Reaches a spread of 5 m with normal vase pruning.

Vigor.—Strong. Approximately 1.8 to 2 meters of growth in the first growing season.

Growth.—Semi-upright.

Productivity.—Very productive.

Bearer.—On one year old shoots.

Fertility.—Self-compatible.

Hardiness.—Hardy in all fruit growing areas of California.

Disease resistance/susceptibility.—No specific testing for relative plant disease resistance/susceptibility has been undertaken. Under close observation in Kern County, Calif., no particular plant/fruit disease resistance/susceptibility has been observed.

Chilling requirements.—About 250 hours at or below 7.2° C.

Trunk: (Measurements were taken at approximately 30 cm above the soil line.).

Diameter.—Approximately 15 cm.

Texture.—Medium shaggy, increasing with age.

Trunk color.—About medium Greyed-Orange 173A becoming darker with age.

Branches: (Measurements were taken at approximately 90 cm above the soil line.).

Size.—Approximately 10 cm.

Texture.—Smooth on young wood, increasing roughness with tree age.

Color.—About medium Greyed-Orange 173A becoming darker with age.

Lenticels.—Present.

Lenticels numbers.—Plentiful.

Lenticels density.—Approximately 12 per cm².

Lenticels color.—About Light Grey 201D.

Lenticels length.—Approximately 3 mm.

Lenticels width.—Approximately 1 mm.

One year old shoots: (Data taken in September at the midpoint of current-season growth.).

Size.—Average diameter approximately 5 mm.

Color.—Topside: About Dark Greyed-Orange 165A.

Underside: About Dark Greyed-Orange 165A.

Internode length.—About 3.0 cm, midway on shoot.

Lenticels diameter.—About 0.3 mm.

Lenticels.—Plentiful.

Lenticels color.—About Light Grey-Brown 199D.

Intensity of anthocyanin on upper side of shoots.—Medium, more prominent in areas that receive more sunlight.

5 Vegetative buds: (Data were taken in September at the midpoint of current-season growth.).

Position of vegetative bud in relation to shoot.—Markedly held out.

Size.—Medium, approximately 1.5 mm×2.5 mm.

Shape.—Ovoid.

Shape of apex.—Obtuse.

Color.—About Dark Brown 200B.

Flower buds: (Data were taken in September at the midpoint of current-season growth.).

10 *Distribution.*—2 flowers buds per node, on one-year old shoots.

Shape.—Obovate.

Dimensions.—Approximately 4 mm×2.5 mm.

Color.—About Dark Greyed-Orange 165A.

15 *Ratio of flower buds to vegetative buds.*—2 flowers buds: 1 vegetative bud.

FOLIAGE

Leaves: (Data taken on fully expanded leaves).

Size.—Medium.

Leaf arrangement.—Alternating.

Average length.—Long; approximately 9.0 cm without petiole.

Average width.—Medium; approximately 2.0 cm.

Ratio of length to width.—Very elongated, approximately 4.5:1 ratio.

Shape.—Lanceolate.

Color of upper side.—About Dark Green 139A.

Color of lower side.—About Medium Green 139B.

Glossiness of upper side.—Medium.

Angle at apex (excluding tip).—Acute.

Shape of base.—Cuneate.

Venation.—Pinately net veined.

Vein color.—About Light Green 139D.

Surface texture.—Smooth.

Shape in cross-section.—Concave.

Profile.—Up-folded.

Leaf blade tip.—Curved downward.

Undulation of margin.—Slight.

Density of pubescence of lower side.—Absent or very sparse.

Incisions of margin.—Crenate.

Petiole:

Length.—Medium; approximately 8 mm.

Diameter.—Approximately 0.7 mm.

Color.—About Light Green 138C.

55 Stipules:

Number/leaf bud.—Approximately 2 when present.

Typical length.—Medium, approximately 8 mm.

Color.—About Dark Greyed-Red 180A when dried.

Persistence.—Falls off.

60 Leaf glands:

Form.—Reniform.

Average number and arrangement.—0-4, usually 2, arranged nearly parallel on petiole.

Diameter.—Approximately 1 mm.

Color.—About Dark Greyed-Red 180A when dry.

Position of nectaries (glands).—On the petiole.

FLOWERS

General:

Time of beginning of flowering.—Very early for the San Joaquin Valley, Calif.

Flower blooming period.—First bloom: Approximately February 9 in Wasco, Calif. Location of First bloom: Toward base of the tree. Full bloom: Approximately February 13 in Wasco, Calif. Location of Full bloom: Central part of the tree canopy.

Duration of bloom.—Approximately 10 days.

Flower diameter.—Medium, approximately 40 mm.

Flower form.—Showy

Pedicel:

Length.—Long, approximately 10 mm.

Diameter.—Approximately 1 mm.

Color.—About Dark Greyed-Red 180A when dry.

Pubescence.—Absent.

Sepals:

Number.—5.

Length.—Approximately 6 mm.

Diameter.—Approximately 4 mm.

Shape.—Triangular.

Color.—About Medium Red 44A.

Texture.—Smooth to slightly bumpy.

Margins.—Smooth.

Position.—Adpressed to petals.

Frequency of flowers with double sepals.—None.

Receptacle:

Depth.—Medium, approximately 2 mm.

Pubescence of inner surface.—Absent.

Pubescence of outer surface.—Absent.

Petals:

Number.—5.

Arrangement.—Slightly overlapping.

Color.—About Medium Red-Purple 62C.

Surface texture.—Smooth.

Length.—Long, approximately 18 mm.

Width.—Approximately 15 mm.

Shape.—Circular.

Apex shape.—Rounded.

Base shape.—Narrows at point of attachment.

Undulation of margin.—Medium.

Frequency of flowers with double petals.—Never.

Pistil:

Length.—Approximately 37 mm.

Ovary diameter.—Approximately 1.5 mm.

Pubescence.—Absent.

Stigma extension in comparison to anthers.—Above.

Frequency of supplementary pistils.—Few.

Stamens:

Number.—Approximately 32-38. Average 34.

Length.—Variable, ranging approximately from 3 mm to 10 mm.

Filament color.—About White 155A.

Pollen color.—About Medium Red 52A.

Position.—Perigynous.

FRUIT

General: (Description taken near Wasco, Kern County, Calif.).

Time of beginning of fruit ripening.—Very early for the San Joaquin Valley, Calif.

Harvest.—

Date of first pick.—Approximately May 29.

Date of last pick.—Approximately June 8.

5 *Maturity when described:* Firm-mature.

Peduncle:

Length of stem.—Short, approximately 7 mm.

Diameter of stem.—Approximately 7 mm.

Color of stem.—About Medium Greyed-Orange 164B.

10 *Size:*

Average size.—Very large.

Diameter in line with suture plane.—Approximately 68 mm.

Diameter perpendicular to suture.—Broad, approximately 68 mm.

Average weight.—Approximately 175 gm.

Height.—Tall, approximately 71 mm.

Shape:

20 *Viewed from apex.*—Circular.

In lateral view, perpendicular to suture.—Circular.

In-line with suture.—Circular.

Symmetry.—Symmetric or slightly asymmetric.

Shape of base.—Slightly depressed.

Shape of apex.—Rounded.

Depth of stalk cavity.—Medium, approximately 10 mm.

Width of stalk cavity.—Medium, approximately 20 mm.

Depth of suture.—Absent or very shallow.

Skin:

Thickness.—Medium, typical of most varieties.

Adherence to flesh.—Strong.

35 *Surface texture.*—Nearly smooth.

Taste.—Neutral.

Reticulation.—Absent.

Tendency to crack.—Rare.

Pubescence.—Absent.

40 *Bloom on skin.*—Absent or very weak.

Ground color.—About Medium Yellow 13C.

Relative area of over color of skin.—Nearly whole surface.

Overcolor.—About Dark Red, ranging from Dark Red 53C to Dark Red 53A.

Pattern of over color of skin.—Solid.

45 *Number of lenticels.*—Few, variable from 0 to 28 per cm^2 .

Size of lenticels.—Very small, approximately less than 0.3 mm.

Flesh:

Ripens.—Evenly.

Texture.—Slow-softening, melting, firm-juicy.

Color.—About Medium Yellow 13C.

Flavor.—Sweet, mid-acid.

Firmness.—Very firm.

Juiciness.—Medium, able to squeeze free juice easily.

Acidity.—Medium for nectarines, 0.75% titratable acidity.

Sweetness.—Medium.

50 *Brix.*—Approximately 14% at harvest

Adherence of stone to flesh.—Adherent.

Fiber.—Medium.

US PP32,463 P2

7

Stone:

Stone freeness.—Clings.

Stone size.—Size: Medium. Length: Approximately 12 mm. Diameter in line with suture: Approximately 10 mm. Diameter perpendicular to suture: Approximately 5 mm.

Color.—About Light Greyed-Orange 164C.

Position of maximum diameter.—Middle.

Stone shape.—Lateral view: Medium elliptic. Basal view: Broad elliptic. Ventral view: Broad elliptic.

10

Base shape.—Nearly straight.

Apex shape.—Pointed.

Ridges.—Rounded throughout.

8

Outgrowing keel.—Well developed.

Ventral edge.—Medium.

Dorsal edge.—Full, deep grooves.

Fibers.—Retains short fiber-like threads along ridges.

Symmetry in lateral view.—Symmetric.

Texture of lateral surface.—Rough.

Width of stalk-end.—Medium, approximately 4 mm.

Tendency to split.—Rare.

What is claimed is:

1. A new and distinct nectarine tree as herein described and illustrated.

* * * * *
